DUSTLESS DROSS RECEPACLE

A Hoyt Levy, Brooklyn, N. Y.

Application February 10, 1933, Serial No. 656,141

5 Claims. (Cl. 220—35)

This invention relates to receptacles for dust-engendering materials and is of particular utility when applied to a receptacle for the fine, powdery dross which accumulates upon the surface of 5 molten lead or lead alloys, although I contemplate the use of the invention in any field for which it may be adapted by the nature of the improvements disclosed herein.

Heretofore, such dross, when skimmed from the 10 molten metal by means of a ladle, has been usually deposited in an open-mouthed receptacle of the conventional drum type, from which the fumes or vapors emanating from the dross are free to rise, accompanied by the dusty components which 15 are characteristic of such refuse.

These dusty, vaporous emanations are of a 20 poisonous nature and quite detrimental to the health of operatives. Prior to my invention, no effective means have been provided to confine 25 the emanations and at the same time permit convenient introduction of the dross into receptacles of a standard type in which the dross can be accumulated for final disposition.

My invention contemplates the provision of a 30 hood capable of application interchangeably to any of a series of containers of the drum type, which may be of substantially conventional and relatively inexpensive structure, the hood being adapted to permit ready introduction thereinto of 35 a dross-charged ladle or ladles repeatedly, and the discharge of the ladle's charge into the container, until it has received its full complement of the refuse, while confining the heated, vaporous and dusty emanations within the hood, and thus preventing the deleterious effects already mentioned.

My invention further contemplates the provision, for the above purpose, of a mural charging opening in one wall of the hood, with a 40 closure urged yieldingly into a normally closed position, so that it will permit passage of the ladle into the hood, but will act automatically to close the charging opening upon withdrawal of the ladle, after the latter has been inverted to 45 discharge the dross through an opening provided in the bottom of the hood, this opening registering with the conventional top opening of the container.

In pursuance of a further object of the 50 invention, means are provided to support the closure in suitable fashion, and to so construct the closure in the inner margin of the charging opening as to form a tight seal against escape of dust.

55 The above, and other objects of the invention

will be clear from the description which follows, and from the drawing, wherein,

Fig. 1 is a top plan view of a receptacle to which one form of my invention has been applied. 5

Fig. 2 is a vertical section of the same, taken on the line 2—2 of Fig. 1.

Fig. 3 is a horizontal section of the same, taken on the line 3—3 of Fig. 2. 10

Fig. 4 is a view, similar to Fig. 1, of a modified form of my invention. 10

Fig. 5 is a vertical section of the same.

Fig. 6 is a similar view of another modified form of my invention. 15

In the practical embodiment of my invention which I have illustrated by way of example, the part designated by the reference character 11 is a metal container which may be, and preferably is, of the familiar "drum" type, only the upper portion thereof being shown, as the lower part 20 may be of usual cylindrical structure and does not require illustration or description. 20

The upright walls of the container 11 preferably terminate in a substantially conventional rim 12 surrounding the usual top-opening 13, 25 and this rim serves, in pursuance of the invention, to support a hood-member 14 which is of suitable structure for combination interchangeably with any of a plurality of containers 11 of the type briefly described above. 30

The hood is made of suitable material, preferably sheet metal. The container is intended to receive dross inserted thereinto through an opening 15 in the bottom of the hood, said opening being arranged to register with the top-opening 35 13 of the container.

The upstanding wall 16 of the hood may desirably be approximately cylindrical in general contour, and vertical throughout at least a portion of its circumference, and tapering outwardly for the remainder thereof toward the top 17. A flange 18, depending from the top, may be welded or otherwise suitably secured to the upper edge of the wall 16, although a removable cover may be employed, with suitable means to hold it in place, such as will readily occur to those skilled in the art, without departing from the spirit of this invention. 40

In further pursuance of the invention, a mural charging opening 19 is provided, at a convenient 50 region, preferably in the front wall flat 20, to permit introduction of a charging ladle, as indicated in dot-and-dash lines at 21, where the ladle is shown inverted, for discharge of the dross through the openings 15 and 13. 55

In order to provide means for complete enclosure of the hood, and thus prevent escape of the dusty, powdery dross or other refuse deposited in the container 11, I have shown in Figs. 1-3, a 5 closure 22, hinged swingingly at 23 upon a horizontal pintle 24 mounted in brackets 25 welded or otherwise suitably secured to the cover member 17.

Said closure is so disposed as to be urged normally into closed position, the disposition thereof being such, however, as to permit the closure to yield resistsingly under the thrusting action of the ladle 21 during the charging operation.

To accomplish this aim of the invention, the 10 closure may be gravity-urged, and/or spring-urged, toward its seat 26, which is shown in Fig. 2 as formed by a flanged extension inwardly of the margin of the charging opening 19.

The front wall 20 and flange 26 are shown as 20 inclined inwardly from top to bottom, so that the closure 22 is urged by gravity against its seat 26. The angle of inclination from the perpendicular need not be great, to create such a tight seal of the charging opening that no dust in poisonous or 25 disagreeable quantities can be emitted therefrom.

As a cognate means to prevent escape of deleterious matter from the container, as well as to effect a sturdy and detachable connection between the container 11 and hood 14, I prefer to 30 form the hood with a base flange 27, adapted to enter a groove 28 in the rim 12 of the container, the upper lip 29 of the rim having cutaway portions at intervals to permit insertion and removal of the flange 28, which may readily be inserted 35 into retentive position into the groove 28 and under the lip 29.

Referring now to Figs. 4 and 5, I have there shown a modified form of hood embodying my invention. In this modification, the front wall 30 40 is vertical, instead of being rearwardly and inwardly inclined, as in Figs. 1 and 3, and the closure 32 hangs in perpendicular position in the charging opening 31, being hinged upon a horizontal pintle 34 carried by the front wall 30 as by 45 means of the bearings 33.

If desired, auxiliary spring means may be provided to urge the closure toward its seat, and for this purpose, I have illustrated, as a further modification, a leaf spring 35, in Figs. 4 and 5, riveted to the top 47 of the hood 44, and having one end engaged with the inner surface of closure 32.

Fig. 6 illustrates in clearer detail, the inside of the hood 44 with the closure 32 hinged at 33 upon the pintle 34, all as shown in Figs. 4 and 5, but 55 with a horizontal spring 49 coiled thereon to aid in closing movement of closure 32.

From the above description, it will be clearly apparent that I have provided an effective means to dispose readily and safely of the dusty dross, 60 or analogous refuse accumulating on molten soft metals, and have thus accomplished the various aims of the invention by a convenient, inexpensive and standardized appliance, capable of meeting the severe requirements of practical use.

65 It will be understood that while I have illustrated and described certain preferred forms of my invention, I do not wish to be understood as limiting myself thereto, but I intend to claim my invention as broadly as may be permitted by the 70 state of the prior art and the terms of the appended claims.

I claim:

1. The combination with a container of the 75 drum type having a top opening surrounded by a horizontal inwardly projecting flange terminat-

ing in an upwardly extending rim, of a protecting hood for the container, said hood comprising an outwardly extending horizontal base flange forming the base of said hood and of an outermost diameter less than that of the rim, and of an innermost diameter substantially equal to that of the top opening, the base flange being adapted to rest on the flange of the container and within the container rim to support the hood and to form a seal between the hood and the container, a top on the hood overhanging the base flange throughout the circumference thereof except at its rearmost point, a wall joining the top and the base flange, all the elements of said wall being inclined downwardly and inwardly except at said rearmost point, said wall having a charging opening at the front thereof, a horizontal flat wall at the bottom of the charging opening in parallel spaced relation to the base flange, triangular flat side walls at the sides of the charging opening, said horizontal and triangular walls projecting inwardly of the container a distance not greater than the width of the base flange, and pivoted closure means for the charging opening adapted to yield inwardly under displacement thereof by a ladle 20 loaded with a charge of dross from molten lead or like metal.

2. A safety hood for use in combination with an open-top container for dusty dross from molten lead or like refuse having a horizontal inwardly projecting flange, said hood having a horizontal, flat closed top overhanging the base flange hereinafter mentioned throughout substantially its entire circumference and a one-piece wall terminating at its lower margin in a horizontal base flange adapted to engage and rest upon the horizontal flange of said container and within the limits of the container and thereby to removably support the hood in the container, said hood having a mural charging opening, a narrow flat wall forming the bottom of the opening, triangular flat side walls extending from the closed top to the narrow flat wall and forming the sides of the opening, and a closure for said opening urged normally toward a closed position but yieldable inwardly to permit introduction of an implement charged with said refuse, said flange surrounding a base opening in the hood adapted to register with the top-opening of said container throughout substantially the entire area thereof whereby the charge can be deposited in the container by a single movement of said implement.

3. The combination with a container having an opening in the top thereof, and an inwardly projecting horizontal flange surrounding the opening, of a removable covering hood for the container, comprising a flat horizontal top wall, a horizontally arranged base flange adapted to rest on and within the periphery of the flange of the container, said top wall overhanging the flange, a partly cylindrical wall extending between the top and the base flange and having a charging opening therein, flat side walls at the sides of the charging opening, an inwardly extending horizontal marginal flat flange at the bottom of the charging opening, said side walls and marginal flange being arranged at substantially right angles to the cylindrical wall, and a closure pivoted inside of the hood and larger than the opening and adapted to normally engage the inner peripheral edge of the marginal flange, said door being swingable forwardly to permit the deposit of material in said container.

4. In a two-member receptacle for the purpose set forth, a container member provided with a

horizontally grooved rim, and a hood member having a generally upright wall opening therein, normally closed by an inwardly swingable closure thereon, and having a horizontal flange adapted to enter the groove of the rim, and a top on said member overhanging said flange.

5. A container hood having a completely circular opening in the bottom thereof surrounded by an annular horizontal flange, adapted to fit with-

in a container, and having a charging opening therein, formed by a pair of flat spaced parallel side walls inclined downwardly and inwardly and a horizontal flat bottom wall joining said side walls, a pivoted closure for the opening, a horizontal closure seat surrounding the opening and arranged above the flange, and a spring adapted to urge said closure toward its seat.

5

A HOYT LEVY.
